PROCESS FOR DEWAXING OILS

Filed July 2, 1934

UNITED STATES PATENT OFFICE

2,119,733

PROCESS FOR DEWAXING OILS

Ulric B. Bray, Palos Verdes Estates, Calif., assignor to Union Oil Company of California, Los Angeles, Calif., a corporation of California

Application July 2, 1934, Serial No. 733,422

17 Claims. (Cl. 196—18)

The present invention relates to a process for separating asphalt and wax from oils containing the same. More specifically, it relates to a process for separating asphalt and wax from oils by means of solvent.

In my co-pending application Ser. No. 466,189, filed July 7th, 1930, I disclosed a process for separating asphalt and wax from oils containing the same. In this process, crude oil, after topping the light oils such as gasoline and kerosene, was commingled with a liquefied normally gaseous hydrocarbon such as propane, under a superatmospheric pressure sufficient to maintain the propane in the liquid state. The mixture was then allowed to settle under pressure to permit settling of asphalt precipitated from solution. The oil solvent solution free from asphalt but containing the wax was decanted from the settled asphalt and passed into a chiller where a portion of the propane was vaporized under reduced pressure which accomplished a refrigerative effect on the remaining oil, wax and propane and caused the precipitation of the wax. By reducing the pressure to approximately atmospheric, the oil was chilled to about —40° F. The precipitated wax was separated from the oil and residual propane by centrifuging and then the wax-free solution was heated to vaporize the propane leaving behind a lubricating oil substantially free from both asphalt and wax.

In my co-pending application Ser. No. 659,855, filed March 6th, 1933 which has been issued as Patent No. 2,010,008, I disclosed that the efficiency of asphalt separation with propane increased as the propane to oil ratio was increased. The higher the propane to oil ratio the more efficient is the separation between the oil and the asphalt. This was evidenced by the fact that greater quantities of asphaltic and semi-asphaltic materials were recovered at the higher propane to oil ratios.

In my application, Serial No. 611,933, now U. S. Patent Number 2,031,095, I have disclosed the use of an asphalt material to promote the crystallization of the wax contained in an oil containing the same. The material is added to the wax bearing oil which does not contain a sufficient amount of the asphalt to promote crystallization of the wax and the mixture is blended with a liquefied normally gaseous hydrocarbon such as propane. The mixture is then chilled to precipitate the wax and the asphalt and wax is separated from the diluted oil.

In my application, Serial No. 610,130, now U. S. Patent No. 2,049,046, I disclosed the co-precipitation of asphaltic material and wax from oils

which have been mixed with a liquefied normally gaseous hydrocarbon. While mixture of oil and diluent is chilled to precipitate the wax in the presence of the asphalt and the precipitated asphalt and wax separated as a mixture from the solution of oil and diluent.

It has also been found that when a considerable amount of high molecular weight propane insoluble tars or asphalt is carried into the propane solution at, say 90 to 120° F. by virtue of the presence of 20 to 40% of oil in the propane solution, a large portion of the dissolved tars or asphalt precipitates in the dewaxing stage by cooling to low temperatures so that the wax cake or slurry is badly contaminated with a heavy resinous impurity which seriously interferes with the handling of the wax upon the filter or in other operations. The precipitation of a small amount of these propane insoluble materials along with the wax is beneficial as regards filtration and settling characteristics of the wax but an excessive amount is definitely detrimental. On account of the equilibrium involved there appears to be little likelihood, however, of so completely deasphaltizing or de-tarring a stock with propane that the benefit of having some asphaltic material present in dewaxing is completely lost by simple propane extraction with a high ratio of propane.

It is, therefore, apparent that it is desirable to deasphaltize or de-tar heavy oil stocks as completely as possible with a relatively high propane to oil ratio before proceeding with the dewaxing of the oil solution. However, economical considerations have restricted conditions to relatively low propane ratios in the initial propane solution or extraction of the stock for the purpose of separating the asphaltic material. This is because the initial amount of propane required to chill the oil to precipitate wax by evaporative refrigeration and to leave an adequate amount of propane at the completion of the chilling operation to provide good settling or filtration characteristics to separate the precipitated wax is rarely over 6 or 7 volumes of propane to one of the oil. For example, if a mixture of 6 volumes of propane to one of oil and wax at a temperature of 90° F. was chilled adiabatically by vaporization of propane under gradually reducing pressure conditions and at a rate, for example, of 3° F. per minute, the amount of propane vaporized to chill the solution to —40° F. would comprise about 3 volumes leaving about 3 volumes of propane in the chilled mixture. The latter amount is more than sufficient to provide good settling or filtra-

tion of the chilled mixture. However, if a topped crude containing approximately 25% asphaltic materials precipitable at 90° F. with a propane to oil ratio of about 12 to 1, the propane to oil ratio 5 of the mixture upon completion of the deasphaltizing operation and as the solution enters the chiller would be in the neighborhood of about 15 or 16 to 1. This amount of propane is far in excess of that required to chill the oil down to -40° 10 F. Furthermore, aside from the fact that the cost of handling such a large amount of propane based upon the amount of oil treated is prohibitive for commercial operations, the filtrate would contain an excessive amount of propane which 15 dissolves an appreciable amount of the wax even at -40° F. so that the pour point of the oil is high upon separation of the propane.

It is an object of the present invention to present a process for separating asphalt and wax in 20 which all of the benefits of a very high propane ratio on heavy oil stocks is obtained without the necessity of standing the cost of such high propane to oil ratios.

It is another object of my invention to separate 25 the asphalt from oils containing the same at a high propane to oil ratio and then separate the wax from the solution at a low propane to oil ratio.

Another object of the invention resides in dis- 30 solving the heavy asphalt and wax containing stock at a high propane to oil ratio sufficient to remove substantially all of the asphaltic and dark coloring bodies from the oil, separating the asphaltic material precipitated from solution and 35 then adding a quantity of waxy oil which is substantially free from asphaltic material so as to lower the propane to oil ratio on the resulting mixture and subsequently dewaxing the mixture.

It is a particular object of my invention to sepa- 40 rate tarry matter from heavy lubricating oil stocks such as from overhead heavy or viscous distillates containing wax or substantially free from wax with a sufficient amount of a liquefied normally gaseous hydrocarbon diluent as propane and then add a clean waxy stock to the de-tarred heavy stock and propane, preferably a light or less viscous waxy overhead lubricating oil distillate substantially free from asphaltic, tarry or coloring bodies in an amount sufficient to lower 45 the amount of propane in the resulting mixture to within a range which is merely sufficient to chill the mixture of oils to a dewaxing temperature by vaporization of a portion of the propane and yet to leave a sufficient amount of propane in the chilled mixture to provide good filtration or 50 separation of precipitated wax from solution, then chilling the mixture to a dewaxing temperature and separating precipitated wax from the remaining propane and oils and finally sepa- 55 rating the propane from the oils and then, if desired, separating the oils into heavy and light fractions such as by distillation. A particular advantage of treating oils in the above manner resides in the fact that the heavy distillates act 60 in such a manner to alter the character of the wax in the light distillate so that when precipitated at low temperatures, the wax may be rapidly filtered.

Other objects and advantages of my invention 70 will be apparent from the following description of the drawing which represents a schematic arrangement of apparatus for carrying out my invention:

Referring to the drawing, an oil containing asphalt and also wax, such as a heavy overhead

distillate cylinder stock or a residual stock is drawn from tank 1 by pump 4 and is passed into line 2 controlled by valve 3 where it meets a stream of asphalt precipitating solvent, preferably a liquefied normally gaseous hydrocarbon 5 which is taken from storage tank 5 via line 6 controlled by valve 7 by means of pump 8 which forces the solution through line 9 into line 2. It will be observed that by the term "asphalt", I intend to include such substantially wax-free 10 fractions which will precipitate or separate from oils when such oils are commingled with liquid propane or other solvents. Such fractions include asphalt or bitumen and/or heavy viscous oil fractions, malthas, pseudo asphaltic materials, tars and dark coloring bodies. 15

The oil solvent solution is passed through turbulence coil or mixing coil 10 and then into decanter 11 where asphalt precipitated from solution by means of the liquefied hydrocarbon is 20 allowed to separate and settle to the bottom of the decanter 11.

For the purpose of precipitating the asphalt from solution, I may employ any of the liquefied normally gaseous hydrocarbons comprising 25 methane, ethane, propane, butane, iso-butane or mixtures thereof. Such hydrocarbons are volatile at atmospheric temperatures and pressures. If desired, I may employ the normally gaseous hydrocarbons obtained by rectification of casing- 30 head gasoline by the so-called stabilizing method now conventional in the natural gasoline industry. Such fractions may comprise the overhead fractions of the stabilizing process. The gaseous fractions may be liquefied by compres- 35 sion and cooling and are drawn off into pressure chambers where they are maintained in the liquid state until they are used. A fraction of this character may comprise essentially propane which, however, may contain other gaseous hy- 40 drocarbons as ethane, iso-butane and butane. Instead of employing a liquefied normally gaseous hydrocarbon for the purpose of precipitating the asphalt, I may also use other solvents which are capable of dissolving the oil and wax from the 45 raw stock but which will precipitate the asphalt. Such solvents may comprise alcohol, mixtures of alcohol and ether, acetone or volatile hydro- 50 carbon solvents such as casinghead gasoline and light naphthas. I find, however, that the process 55 is best carried out by the use of liquefied normally gaseous hydrocarbons, preferably liquid propane, in the ratio of approximately 10 to 20 volumes of propane to one of the oil and in the present discussion of my invention, I shall describe the process employing propane although I do not wish to be specifically limited thereto.

A superatmospheric pressure is maintained in decanter 11 sufficient to maintain the propane and oil in the liquid state at the temperature in 60 decanter 11. Decanter 11 and solvent storage tank 5 are maintained at substantially the same pressure by means of equilibrium line 12 controlled by valve 14. For the solvent given above, i. e. propane, this pressure should be about 125 lbs. per square inch when a temperature of about 75° F. is maintained in decanter 11. At higher temperatures, the pressures will be correspondingly higher.

The asphalt precipitated from solution by 70 means of propane and settling to the bottom of decanter 11 is removed as a slurry of asphalt containing oil and propane. This asphalt slurry is removed via line 15 controlled by valve 16 by means of pump 17 which forces the slurry via 75

line 18 through heater 19 where the mixture is heated to a sufficiently high temperature to melt the asphalt and vaporize the residual propane. This mixture is then flashed via valve 21 on line 5 20 into vaporizer 22 which is operated at a lower pressure. Superheated steam is introduced into vaporizer 22 via line 23 to supply additional heat and to reduce the asphalt to proper specification generally only as regards flash and fire points. 10 The overhead from vaporizer 22 is sent through line 24 to cooler 25 where the water and oil vapors are condensed which then pass via line 26 into separator 27. Any condensed light oil in separator 27 is withdrawn through line 28 controlled by valve 29 and condensed water is withdrawn via line 30 controlled by valve 31. The uncondensed propane from separator 27 is sent through line 32 controlled by valve 33 to the suction of compressor 34. Also, the propane vaporized in other apparatus in the process, as will be described, will be sent to compressor 34. The propane is compressed in compressor 34 where the pressure is raised so that in the high pressure system and the compressed propane is passed via 15 line 35 to condenser 36 where the propane liquefies and thence passes via line 37 to propane storage tank 5.

The asphalt is withdrawn from the bottom of vaporizer 22 via line 38 controlled by valve 39 by 20 means of pump 40 which forces the asphalt through line 41 into asphalt storage tank 42.

The overflow from decanter 11 consisting of 25 substantially asphalt-free oil, wax and propane in a ratio in excess of that introduced into decanter 35 11 due to the separation of a part of the oil as asphalt is withdrawn via line 43 where it is commingled with 1 to 3 volumes of waxy oil substantially free from asphalt such as low viscosity distillate or a well chemically treated oil coming 40 from tank 44 via line 45 controlled by valve 46 and pump 47 which forces the oil via line 48 into line 43. This mixture then passes through heater 49 and line 50 controlled by valve 51 into chiller 52 where the mixture is chilled to a sufficiently 45 low temperature to precipitate wax from solution. In heater 49, the mixture is heated to sufficiently high temperature to cause the wax to dissolve in the oil and propane preparatory to dewaxing.

The amount of waxy oil commingled with the 50 decantate from the asphalt separator 11 will depend largely upon the propane to oil ratio passing into line 43 and also upon the desired propane to oil ratio passing into chiller 52. If the original oil in tank 1 contains approximately 55 11% of asphalt and is commingled with, say 12 volumes of propane at 90 to 120° F. and approximately 10% of asphalt is removed in decanter 11, the propane to oil ratio in line 43 will comprise about 13 to 1. Adding, say 2 volumes of distillate from tank 44 to the propane and oil in line 43, the propane to waxy oil ratio will be in 60 the neighborhood of 4.3 to 1 which is in the region commonly accepted as being economical. Adding 3 volumes of the waxy distillate would give a still lower propane ratio in the neighborhood 65 of 3.3 to 1, while the addition of only one volume of waxy distillate would give a higher ratio of about 6.5 to 1.

The chilling for dewaxing in chiller 52 is accomplished by vaporizing a portion of the propane under reduced pressure which exerts a refrigerative effect upon the remaining oil, wax and propane. By gradually reducing the pressure at a rate of, say 2 to 5° per minute down to substantially atmospheric pressure, a temperature of app-

proximately -40° F. is obtained in chiller 52 which is sufficient to precipitate substantially all of the wax from solution. When other solvents are used, the refrigeration temperature at atmospheric pressure will vary from -40° F. and in some cases, it may be necessary to operate the chiller at sub-atmospheric pressures or to chill the solution by indirect heat exchange with a cold medium such as brine. The propane vaporized in 5 52 passes via line 53 controlled by pressure reduction valve 54 and passes into line 32 to the suction of compressor 34. The chilling in 52 may be accomplished with or without make-up propane depending upon the propane to waxy oil ratio entering the chiller and the ratio of propane to oil desired at the completion of the chilling operation. If the propane to oil ratio entering the chiller is insufficient so that upon evaporation of propane to atmospheric pressure, an insufficient amount of propane remains in the 10 chiller to provide for adequate separation of the precipitated wax from the remaining oil and propane, a further quantity of propane may be added via line 55 controlled by valve 56. This liquid propane may be either precooled or not, depending upon whether it is desired to obtain further chilling in 52 with the make-up propane. If it has been found that the propane to oil ratio was sufficient to obtain the desired low temperature but insufficient to provide for adequate wax separation, it is preferable to add propane cooled to about -40° F. into chiller 52 through line 55, whereas, if the propane was insufficient to produce the desired refrigeration, the propane may be added at a somewhat higher temperature. 15 The chilling may then be continued to -40° F. It is generally desirable to complete the chilling operation with propane to oil ratio of about 2 to 2½ to 1. This is sufficient to accomplish good separation of the precipitated wax from the 20 chilled mixture.

The chilled mixture is withdrawn from the bottom of chiller 52 via line 57 controlled by valve 58 and pump 59 which forces the mixture under pressure via line 60 through filter 61 where the 25 precipitated wax deposits upon the filter leaves and is withdrawn via line 62 controlled by valve 63 from which it may be passed to suitable heaters and separators for removing propane and oil contained in the wax cake. Instead of separating the precipitated wax by filtration, I may employ other means, such as cold settling or centrifuging. The filtrate substantially free from wax and asphalt is passed through line 64 through heat exchanger 65 where the low temperature of 55 the solution may be recovered such as by heat exchange as, for example, with solution entering the chiller after passing through heater 49. The mixture is then introduced into vaporizer 66 where the propane is vaporized, aided by steam 60 circulated through closed coil 67. The vaporized propane passes out of vaporizer 66 via line 68 controlled by valve 69 and thence passes into line 32 to the suction of compressor 34. The dewaxed oil passes from the bottom of vaporizer 65 66 via line 70 controlled by valve 71 and pump 72 which forces the oil through line 73 into storage tank 74.

After dewaxing and depropanizing, the mixture of heavy and light oil stocks may be redistilled and fractionated to give appropriate cuts for further treatment such as with acid and alkali and clay or by extraction with suitable solvents such as liquid sulphur dioxide, or for use as different viscosity grades of lubricating oils, if 70 75

desired. This may be effected in a fractional distillation column 15 supplied from the tank 14 by means of line 16, and having take off lines 17 for the recovery of various fractions as desired.

5 The following represents an example for carrying out my process on certain stocks. However, this example is not intended to be limiting:

An S. A. E. 70 overhead vacuum distilled stock containing wax was mixed under pressure with 10 about 20 volumes of propane at 90° F. which caused separation of about 12% of heavy greenish-brown tar. After decantation, the propane oil solution was commingled with twice as much of S. A. E. 40 distillate stock based on the original 15 oil giving a propane to oil ratio of about 6.8 to 1. This solution was heated to above the cloud point (about 125° F.) and then chilled adiabatically at a rate of about 2½° F. per minute to about -40° F. and then was filtered at -40° F. under a pressure 20 of about 10 lbs. per square inch. The volumetric ratio of propane to oil passing to the filter was about 3.3 to 1. The filter rate on a viscous oil basis was 3.9 gallons per square foot per hour. After treating the oil with a selective solvent in 25 the presence of the remaining propane, a raffinate was obtained having a gravity of 60° F. of 27.3° A. P. I., a color of 7 N. P. A., a pour point of 5° F., Saybolt Universal viscosities of 1185 at 100° F., 474 at 130° F., 182 at 170° F. and 92.5 at 210° F., a 30 viscosity index of 88 and a viscosity gravity constant of 0.811.

It will be observed that in addition to obtaining a very thorough de-tarring of the heavy stock without the expense of propane to oil ratio being 35 charged against the heavy stock by the method shown above, another important advantage is obtained in that the dewaxing characteristics of the added lower viscosity stock are greatly improved by the admixture with the heavy stock.

40 It will be observed that while I have described the foregoing example in connection with treating an S. A. E. 70 overhead vacuum distilled stock and commingling an S. A. E. 40 distillate with the deasphaltized heavy stock and then dewaxed the mixture, the invention may be applied to the treatment of other oils. Thus, instead of adding an S. A. E. 40 distillate to the heavy stock, I may add a treated waxy distillate such as one which had been refined with acid and alkali or with a 45 selective solvent such as liquid sulphur dioxide or both. Instead of treating a heavy overhead distillate, I may treat a raffinate produced by selective solvent extraction with liquid sulphur dioxide and obtain an improved color and carbon residue 50 on the raffinate. The treatment with large amounts of propane appears to precipitate color bodies from the raffinate which even selective solvent extraction will not remove.

Thus, there are many variations of the process 60 which may be made within the scope of the following claims by those skilled in the art without departing from the spirit of the invention; consequently, the foregoing exemplary description is not to be taken as limiting.

65 I claim:

1. A process for separating asphalt and wax from oils which comprises mixing a heavy oil containing asphalt and wax with a sufficient quantity of liquefied normally gaseous hydrocarbon 70 diluent to effect precipitation of substantially all of the asphalt from said oil, separating precipitated material from the oil and hydrocarbon diluent, commingling said oil and diluent with a wax containing oil in amount sufficient to reduce 75 the diluent oil ratio to a large extent, chilling said

mixture to precipitate wax, separating precipitated wax from said mixture, and subjecting the dewaxed oil to distillation to separate the same into oils of varying viscosities.

2. A process for separating asphalt and wax 5 from oils which comprises commingling an oil containing asphaltic material and wax with a liquefied normally gaseous hydrocarbon diluent in an amount sufficient to separate substantially all of the asphalt and coloring matter from said 10 oil, said hydrocarbon diluent to oil ratio being considerably in excess of a diluent to oil ratio desired during dewaxing of an oil by vaporization of diluent under reduced pressure, separating precipitated asphaltic material from the oil and diluent, commingling said oil and diluent with a sufficient amount of an asphalt-free waxy oil of lower viscosity than said first mentioned oil to reduce the diluent to oil ratio within an amount desirable for dewaxing by vaporization of diluent 15 under reduced pressure, chilling said mixture to precipitate wax and separating precipitated wax from said mixture.

3. A process as in claim 2 in which said heavy oil containing asphalt comprises about an S. A. E. 25 70 oil and said waxy lighter oil comprises one having about an S. A. E. 40.

4. A process for separating wax from relatively light waxy oils which comprises commingling said relatively light waxy oil with a light hydrocarbon 30 diluent and a raffinate produced by extracting an oil with a selective solvent, said raffinate containing color bodies which are not removed by the extraction with the selective solvent but which precipitate when admixed with said light hydrocarbon diluent, chilling said mixture to precipitate wax and separating the precipitated wax from the mixture.

5. A process for separating wax from waxy oils which comprises commingling a relatively light 40 waxy oil with a light hydrocarbon diluent and a relatively heavier raffinate produced by extracting an oil with a selective solvent, said raffinate containing color bodies which are not removed by the extraction with the selective solvent but 45 which precipitate when admixed with said light hydrocarbon diluent, chilling the mixture to precipitate wax and separating precipitated wax from the mixture.

6. A process for separating asphalt and wax 50 from oils which comprises commingling an asphalt and wax containing oil with a large volume of solvent capable of dissolving the oil but not the asphalt, separating undissolved asphalt from the oil and solvent, commingling said deasphalted oil and solvent with a second oil containing wax but substantially free from asphalt in amount sufficient to reduce the diluent oil ratio to a large extent, chilling said mixture to precipitate wax and separating precipitated wax 60 from said mixture.

7. A process for separating asphalt and wax from oils which comprises mixing a heavy oil containing asphalt and wax with a sufficient quantity of liquefied normally gaseous hydrocarbon 65 diluent to effect precipitation of substantially all of the asphalt from said oil, separating precipitated asphalt from the oil and hydrocarbon diluent, commingling said oil and diluent with a wax containing oil substantially free from 70 asphalt in amount sufficient to reduce the diluent oil ratio to a large extent, chilling said mixture to precipitate wax and separating precipitated wax from said mixture.

8. A process as in claim 7 in which the liquefied 75

normally gaseous hydrocarbon diluent comprises liquid propane.

9. A process for separating wax from waxy lubricating stocks which comprises commingling 5 a relatively heavy raffinate with large quantities of a liquefied normally gaseous hydrocarbon diluent, said raffinate being produced by extracting an oil with a selective solvent but containing color bodies which are not removed by the extraction 10 with the selective solvent, adding a quantity of a relatively lighter waxy oil to reduce the oil-diluent ratio, chilling the mixture to precipitate wax and separating the precipitated wax.

10. A process for separating wax from oils 15 which comprises mixing a waxy heavy oil which naturally contains a wax separation aid with a sufficient quantity of a diluent which is capable of precipitating said wax separation aid from said oil, and thereby precipitating wax separation aid, 20 separating substantially all of the wax separation aid from the diluted oil, mixing said diluted oil with an oil containing wax in an amount sufficient to reduce the diluent to oil ratio, chilling said mixture to precipitate wax and separating the 25 wax from said mixture.

11. A process for separating wax from a relatively light waxy oil which is substantially free from asphalt which comprises mixing a relatively heavy waxy oil containing asphaltic materials 30 with a light hydrocarbon diluent in an amount sufficient to precipitate a substantial quantity of said asphaltic materials but to leave a small quantity of the asphaltic materials in the oil to serve as a wax-separation aid for the subsequent 35 dewaxing of relatively light waxy oil, mixing said diluted oil with a relatively light waxy oil in an amount sufficient to reduce the diluent to oil ratio to a large extent, chilling the mixture in the presence of the wax separation aid to precipitate the wax and separating the precipitated 40 wax from the mixture.

12. A process as in claim 11 in which the light hydrocarbon diluent comprises a liquefied normally gaseous hydrocarbon.

13. A process as in claim 11 in which the light hydrocarbon diluent comprises liquid propane.

14. A process for separating wax from a relatively light waxy oil which is substantially free from asphalt which comprises fixing a relatively 5 heavy waxy oil containing asphaltic materials with a light hydrocarbon diluent in an amount sufficient to precipitate a substantial quantity of said asphaltic materials but to leave a small quantity of said asphaltic materials in the oil 10 to serve as a wax separation aid for the subsequent dewaxing of the relatively light waxy oil, removing the precipitated asphaltic material from the oil, diluent and remaining asphaltic materials, mixing said last mentioned mixture 15 with the relatively light waxy oil in an amount sufficient to reduce materially the diluent to oil ratio, chilling said mixture to precipitate wax and separating the precipitated wax from the mixture.

15. A process for separating wax from waxy lubricating stocks which comprises commingling a relatively heavy wax bearing raffinate with large quantities of a light hydrocarbon diluent, said 20 raffinate being produced by extracting an oil with a selective solvent and containing color bodies which are not removed by the extraction with the selective solvent but which precipitate when admixed with said light hydrocarbon diluent, precipitating and separating said color bodies from 25 said raffinate and diluent, adding a quantity of a relatively lighter asphalt free waxy oil to reduce the oil-diluent ratio, chilling the mixture to precipitate wax and separating the precipitated wax from the solution of diluent and oil.

16. A process as in claim 15 in which the light hydrocarbon diluent comprises a liquefied normally gaseous hydrocarbon.

17. A process as in claim 15 in which the light hydrocarbon diluent comprises liquid propane.

ULRIC B. BRAY.
